FISHING GAME WELL

James Windell Ganus, 463 Topaz St., and Robert Victor Fuchs, 4951 Hauck Drive, both of New Orleans, La.

Filed Apr. 16, 1971, Ser. No. 134,920

Term of patent 14 years

Int. Cl. D21-01

U.S. CL. D34—15 R

The sole figure of the drawing is a perspective view of the well. The device is symmetrical and consequently the view from the rear side would be a mirror image of the one shown in the single figure.

We claim:

The ornamental design for a fishing game well, as shown and described.
